CLAIM

The ornamental design for a swab, as shown and described.

DESCRIPTION

FIG. 1 is a top, plan view of a swab showing my new design;

FIG. 2 is a front elevation view thereof;

FIG. 3 is a left side elevation view thereof;

FIG. 4 is a right side elevation view thereof;

FIG. 5 is a bottom plan view thereof;

FIG. 6 is a rear elevation view thereof;

FIG. 7 is an enlarged, fragmentary, front, elevation view thereof; and,

FIG. 8 is a left, front, and top perspective view thereof.

The features shown in broken lines in FIGS. 1–8 depict environmental subject matter only and form no part of the claimed design.

The broken line which defines the bounds of the claimed design forms no part thereof.
